UNITED STATES PATENT OFFICE.

WILLIAM D. RIGNEY, OF PORT CHESTER, NEW YORK, ASSIGNOR TO RUSSELL, BURDSALL & WARD BOLT AND NUT COMPANY, OF PORT CHESTER, NEW YORK, A CORPORATION OF NEW YORK.

NUT-TAPPING MACHINE.

1,147,267.

Specification of Letters Patent.

Patented July 20, 1915.

Application filed October 23, 1914. Serial No. 868,240.

To all whom it may concern:

Be it known that I, WILLIAM D. RIGNEY, a citizen of the United States, and residing at Port Chester, in the county of Westchester 5 and State of New York, have invented a new and Improved Nut-Tapping Machine, of which the following specification is a full disclosure.

This invention proposes various improvements in nut-tapping machines, and it deals more especially with machines of the continuous type employing a floating tap which is positioned by the agency of the nut-blanks.

15 One object within the contemplation of this invention is to render available a nut-tapping machine which will operate continuously without the loss of time occasioned by the substitution of one tap for another, 20 and in which the various operations will take place smoothly and efficiently, and which will be designed to present a rugged and durable structure capable of withstanding long and hard service.

25 Another object is to create a nut-tapping organization which will enable the blanks to be tapped in succession without permitting them to bind on and break the tap through a "nut-lock" action, and which will 30 promote the free travel of the nut-blanks along the shank of the tap by so avoiding or overcoming the friction of the guiding elements that a cramping or congesting of the train of nuts will be precluded.

35 Another object is to devise a nut-tapping mechanism in which the nut-blanks may be threaded at a high rate of speed without causing an undue heating of the tool or an undue accumulation of the chips by providing means for maintaining the tap in a forced stream of coolant flowing so rapidly as to wash away the chips as quickly as formed and to keep the tool thoroughly cooled.

45 Another object is to provide a simple and inexpensive structure whereby the nut-blanks will be brought automatically into correct registry with the socket of the chuck notwithstanding the high speed of the latter, 50 and without permitting any clogging up of the apparatus, and avoid the likelihood of

fracture by permitting of the use of rugged and substantial elements.

Another object is to render available a safety-control instrumentality which may be relied upon to stop the feeding of nut-blanks into the machine in case the tap should be broken or in case it should become congested with nut-blanks or become otherwise disabled, and to so devise this instrumentality that it may be capable of instant action without depending upon overcoming the inertia of rapidly moving parts such as is necessitated by the stopping of the machine itself.

Other objects will be in part obvious from the annexed drawings and in part indicated in connection therewith by the following analysis of this invention.

This invention accordingly consists in the features of construction, combinations of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference, denote corresponding parts throughout all the views of which:

Figure 1 is a side elevation of the assembled machine showing the general arrangement thereof. Fig. 2 is a detail of the floating tap employed in this machine. Fig. 3 is a horizontal section through the tooling portion of the machine showing certain details of the blank-feeding plunger, the chuck for receiving and rotating the nut-blanks relative to the tap, as well as the automatic stop controlling the feed of the blanks. Fig. 4 is an elevation of the machine at the discharging end thereof showing details of the finger mechanism for promoting the travel of the tapped nut-blank in the discharging direction. Fig. 5 is a section through line 5-5 of Fig. 4 showing further details thereof. Fig. 6 is a transverse section taken through line 6-6 of Fig. 1 showing certain

details of the driving gearing. Fig. 7 is a transverse section through line 7—7 of Figs. 1 and 12 showing details of the automatic stop-mechanism for controlling the feed of the nut-blanks. Fig. 8 is a section through line 8—8 of Fig. 1 showing further details of the automatic stop-mechanism. Fig. 9 is a fragmentary perspective of the automatic stop-mechanism. Fig. 10 is a perspective of 10 one of the elements of this machine. Fig. 11 is an end elevation of the chuck for receiving and rotating the nut-blanks with relation to the tap. Fig. 12 is a plan showing the machine completely assembled and illustrating 15 various details thereof.

By way of a more general analysis, it may be observed that this invention contemplates the use of a tap preferably of the "floating" type, as indicated by A, and which is supported solely through the agency of the nut-blanks themselves. This tap A has an "offset" shape designed to enable it to resist displacement in all directions, and it comprises a tooling portion 1 constituting the tap proper having conventional relieved cutting threads which are adapted to enter the hole of a nut-blank to cut internal threads therein in the usual manner. The tap portion is connected with a reduced shank portion 2 which, at a suitable point, forms an elbow 3 of a sufficiently great radius to permit of easy passage of a train of nut-blanks. The shank of the tap in this instance continues in the form of portion 4; the axis of which is 25 inclined to the axis of the tap proper 1; preferably at right angles thereto. In operation, the tap and its above described offset shank carry a train of blanks somewhat as shown. In the preferred form of this invention, the direction of travel of these blanks is indicated by arrow 5 of Fig. 2.

The means for starting a nut-blank on the tap comprises a member B (see Figs. 2 and 3) in the nature of a plunger which is adapted to abut endwise against a blank to shift it laterally so as to telescope the blank over the end of the tap and enable it to be seized by the threads of the tap so that thereafter the tap may assume control of the blank and 30 draw it progressively in an axial direction over all of the threads of the tap and through the socket of the chuck, as will be understood. At the moment that this plunger B urges the nut-blank against the end of 35 the tap, a force is exerted which moves or tends to translate the tap in the direction of its axis, and, unless it is properly resisted, such tap would be forced into an inoperative position. This displacement is prevented 40 from taking place to any consequential extent by means of an abutment surface 6 which is preferably provided by a positioning member or guide C. This abutment surface 6 extends parallel with the axis of the 45 off-set extension 4 of the tap on the side

thereof remote from tap proper 1, so that, when the tap tends to move before the advance of the plunger B, the nut-blanks D entrained by the tap-shank will be pressed against the surface 6 and will restrain further displacement of the tap A. 70

The means for producing relative rotation between nut-blanks and the tap will comprise a member such as E which is in the nature of a chuck in that it has a nut-receiving socket 7 configurated so that the blanks may travel therethrough without, however, being permitted to rotate relatively to the chuck or blank holder E. That is to say, the blanks may translate but not 80 rotate relatively to the holder or chuck; although a relative rotary motion will simultaneously exist between the tap and both the holder and its blanks. This creates a relative rotation between the blank and the tap; accompanied by a sliding shift of the blanks along the walls of the socket of the blank-holder. In undertaking to render more practical this general type of machine, I have observed that the effect of this is to 85 create considerable friction between the blanks and the walls of the socket and this friction must be overcome by the pull of the tap itself. In other words, the plunger, at the instant of engaging a blank with the threads of the tap, forces the tap in a direction to move this extension 4 toward the bearing-surface 6, until resisted by the physical impact of the nut-blanks on the off-set portion with said surface 6; whereas, the 90 instant the tap assumes control of the blank, it tends to pull the blank through this holder or chuck and this tends to shift the tap in an opposite direction so as to move the extension 4 away from the surface 6. 95 The extent of this opposite movement is, however, limited by impact of the nut-blanks with a complementary bearing-surface 8 which extends in parallelism with the surface 6 but which is located on the opposite side of the extension 4. So long as the tap is drawing a nut-blank through the bore of the holder E, and while no opposing pressures are being exerted by the plunger B, the threaded nut-blanks on the extension 100 105 110 115 a force supplementing or independent of that derived from the threading action of the tap and preferably so applied as to become effective either at a definite time in 5 the cycle of operations or whenever the friction at the surface 8 is reduced or relieved. Thus, this invention contemplates an element such as the finger indicated by F which is preferably impositively actuated, 10 as by means of a spring or a weight, and which bears against one of the blanks of the train so as impositively to urge forward the section of blanks beyond the point of contact. Now, if the friction created at 15 the point 8 by the drawing-in action of the tap is not unduly excessive, the train of blanks will be caused to slip in the discharging direction under the insistence of the finger F; but, should the friction at 8 be excessive, then will the shifting of the blanks be 20 momentarily suspended until the plunger B comes into action to urge a nut-blank onto the end of the tap. This tends to shift the tap in opposition to its drawing-in action 25 and creates a relief of the friction at the point 8 by momentarily shifting the off-set portion 4 toward the surface 6 and, during this momentary relief, the finger F will be able to push the section of blanks through 30 the guide C along the off-set shank. In the normal operation of the machine, this work will be done more or less irregularly depending, of course, upon the variations in the pull on the tap 1 as it threads the successive nuts; but at no time will any congestion be permitted and the various blanks will all be free to leave the threads of the tap in finished form without being opposed by a more or less severe counter-pressure of 40 the already finished blanks. One of the difficulties which has heretofore rendered impracticable a machine of this type has thus been overcome.

Another difficulty has been that the off-set 45 floating tap has tended to become cramped in its support by a lateral displacement adjacent its elbow. I have ascertained that there is a considerable tendency of the L-shaped tap to swerve askew at a point adjacent the elbow and I have found that by 50 providing an anti-friction bearing, such as the anti-friction roller G, so as to support the train of blanks on the tap adjacent the elbow, that the smooth working of the operation will be materially enhanced.

The torque of the tap, created by the relative rotation between the nut-blanks and the threads of the tap, is received by the bearing surface 9 (see Fig. 1) which extends parallel 55 with the bearing surfaces 6 and 8 and, like the latter, is arranged in off-set relation with the axis of the tap proper to produce the necessary moment-arm. The turning of the nut-blanks with relation to the threads 60 of the tap results from the relative move-

ment between the nut-chuck E and the member C which as a single unit preferably carries the surfaces 6, 8 and 9 and in this instance, the member C is stationary with the frame of the machine and the nut-holder E 70 is bodily rotated.

In order to carry out the cycle of operations demanded for the above-mentioned major elements, various specific constructions may be resorted to and by way of illustration there has been shown herein a very simple and essentially practicable construction which may now be described.

The nut-chuck E is shown in section by Fig. 3 and comprises a hub portion 10, 80 which, in this instance, is journaled in a portion 11 of the main frame and is retained in place as by means of a ring 12 which fits over the flange 13. This chuck has a socket 7 adapted to receive the nut-blanks 85 and to rotate the same by engaging the polygonal sides of said blanks. To that end, the socket 7 provides walls in the nature of guides for the sides of the nut-blanks and to enable a copious flow of coolant to pass 90 freely around the blanks so as to wash away the chips made by the tap. This socket preferably provides canals or channels as indicated by 14 on Fig. 11. In normal use, this chuck revolves rapidly, and inasmuch as the 95 blanks are not revolving when feeding toward it it is essential to provide some means for bringing the blanks into angular registry with the walls of the socket. This invention, therefore, accomplishes this by 100 mounting a series of hardened steel balls 15 at the entrance of the socket of the chuck. These balls are secured in place in any appropriate manner, as by flattening the non-exposed faces thereof, and securing them in 105 place by means of set-screws so that they will revolve in unison with the chuck and will present their polished surfaces to be contacted by the blanks which are guided into registry with the socket of the chuck. 110

In practice it is found that this arrangement quite efficiently performs its office. The chuck may be revolved or driven in any suitable manner, as by means of the ultimately driven gear 16 which is driven in turn by a pinion 17 mounted on the main shaft 18 which is journaled in pillow blocks 19 and 20 mounted on the main frame of the machine, and which shaft carries a loose pulley 21 and a fast pulley 22 which may be 115 driven from a suitable source of power by means of a belt 23, as will be understood. In this way the nut-chuck is maintained in a continuous state of rotation.

The nut-blanks are fed intermittently into the socket of the nut-chuck by means of a reciprocating member B, here instanced as a tube, secured in a socket in the end of the actuator 24 (see Fig. 3) and removably held in place by means of a set-screw 25 120

to permit of replacement in case of damage. The actuator 24 is mounted slidably to reciprocate in bearings 26 provided by the frame of the machine so that during each stroke of the actuator 24 the plunger B will take possession of a nut-blank and shift it laterally past the balls 15 and thence into the socket 7 and into engagement with a tap exactly arranged therein. The actuator 24 is reciprocated impositively during this forward stroke and positively during its return stroke. That is to say, the forward stroke is executed by means of the yoked end 27 (see Fig. 8) of the arm 28 extending upwardly from a rocker 29 which is pivoted at 30 to the frame, and is in turn actuated by a link 32 pivoted to its lower arm 31. The other end of this link 32 is pivoted to the upper arm 33 (see Fig. 6) of a bell crank lever 34 which is constantly urged clockwise by means of a weight 35 attached thereto through the rod 36. The advantage of utilizing an impositive force for effecting the forward stroke of the actuator lies in the fact that parts will not be broken should they meet with an obstruction due to the clogging or congesting of the nut-blanks on the tap or in the chuck.

The withdrawal or return stroke of the actuator may be effected positively as by means of roller 37 (see Fig. 3) which is mounted at one side of the depending arm 31 and is periodically moved to the left by impacting with the peak 38 of the cam 39 which is secured to a power-shaft 40. This power-shaft extends alongside of the machine and is journaled thereto by means of the pillow blocks 41 and 42 and it carries a large driven gear 43 that is driven by a pinion 44 secured to a large gear 45, and which is in the first instance driven by a pinion 46 secured to the main power-shaft 18.

The nut-blanks are brought within the sphere of operations of the intermittent plunger by means of a chute 47 (see Fig. 1) which is positioned by means of a bracket 48 and receives its supply of blanks from an overlying hopper. This chute preferably has a depending lug 49 pivoted at 50 to the frame so that it may be moved to one side by releasing the set-screw 51 (see Fig. 1) and thus permit access to be had to the parts.

The automatic stop for the nut-feed.—In this embodiment, the nut-blanks descend in the form of a train through an appropriate chute 47 in such a manner that the lowest blank will drop into the path of the reciprocating plunger B which shifts it laterally into the blank-chuck and onto the tap. Now, in case the tap should become broken or disabled the nut-blanks would accumulate and congest within the chuck under the actions of the reciprocating plunger and serious damage would be done to the machine. This

is prevented automatically, however, by a mechanism which discontinues the supplying of the blanks in the event of an abnormal action of the mechanism. The construction preferred for this purpose may now be described.

Referring to Figs. 1 and 7, the power-shaft 40 is provided with a cam 52 having a peak 53 located at an appropriate point in the cycle of operations of the machine. A lever 54 is pivoted to the frame of the machine at a point indicated by 55 so that it may be enabled to be rocked in a given plane, which in this instance is vertical. This lever extends toward the blank-chute 30 and terminates in a finger 56 adapted when the lever is rocked to swing into the path of the blanks and obstruct the descent thereof. The other end of the lever terminates out of the path of the cam 52 and carries a pawl 57 which is pivoted to it at a point 58 so that such pawl swings transversely to the said given plane of oscillation of the lever 54. This pawl terminates in a contact-piece 59 which is adapted to be brought into the path of the cam 52 so that in the event of contact, the cam may shift it transversely to its plane of oscillation and thereby move the lever 54 and its finger 56 into the path of movement of the blanks. A spring 60 secured to the frame of the machine constantly urges the pawl into the path of the cam and this is the normal position of said pawl so that, unless it is displaced against the resistance of the spring 60 by a means about to be mentioned, the finger of the lever will be shifted into its obstructing position against the resistance of spring 61 at each cycle of operations of the machine. The pawl 57 is, however, so constructed and arranged in relation to a part moving in unison with the plunger that it will be thrown out of the path of the cam whenever the plunger reaches a station near the end of its forward stroke. That is to say, a finger 63 constitutes a contact element which advances in synchronism with the advance of the plunger and which, at a predetermined station in such advance, impacts with a foot 62 forming a part of the pawl 57 so as to swing the pawl clockwise against the resistance of the spring 60 and thus bring its contact end out of the path of the cam. In these circumstances, the cam 52 will be ineffective to actuate the lever 54 and the spring 61 will maintain the finger 56 out of the path of descent of the nut-blanks; with the result that the nut-blanks are free to gravitate into the path of the plunger during the successive strokes thereof. An automatic stop action takes place, however, whenever the plunger fails to complete its full forward stroke for the reason that the finger 63 fails, in that event, to bring the pawl out of the path of the cam; with the result that, at a definite 125

station in the cycle of operations, the cam throws the obstructing finger into the path of travel of the blanks against the resistance of spring 61 and prevents further feed of 5 the blanks.

By means of the elements above described, it will be understood that the blanks will be fed at appropriate intervals into the tooling action of the tap so that they will be 10 properly threaded thereby and discharged at spaced intervals onto the shank of the tap. While the tapping of each blank has a continuous operation, it is, nevertheless, to be noted that the bringing of the successive 15 blanks into the sphere of action is executed intermittently so as to leave appropriate intervals or spaces between the successive blanks while on the tap, and, consequently, any possibility of a "nut-lock" effect 20 is avoided. This structure is, therefore, from one aspect, characterized by the fact that it intermittently, as distinguished from continuously, feeds non-rotating blanks into a rotating blank chuck and then urges the 25 rotating blanks onto a stationary tap, and then permits the nut-blanks to draw themselves through the chuck by their forced rotation with relation to the tap. The tooling action of the tap engenders considerable 30 heat which tends to impair the hardness of the metal, and it also forms chips which tend to obstruct the passage of the blanks and to clog the tap. This invention, however, proposes means for effectively 35 overcoming this difficulty.

The chip remover and tap cooler.—The plunger B has a central passage way 64 which registers with the bore 65 of the actuator 24, and by means of a nipple 66 this 40 actuator is in turn connected with a tube 67 which receives a forced flow of a suitable coolant, such as water or the like, delivered through the flexible tube 68 by means of a pump 69 driven continuously as by 45 means of a belt 70 deriving motion from a suitable pulley on the machine. This pump is so designed as to be capable of delivering a volume of fluid greatly exceeding that ordinarily employed for the mere lubrication 50 of the cutting threads of a tap. That is to say, the flow of coolant is so copious that the tap is not only kept cool, notwithstanding its high speed and continuous action, but the chips are all forcibly washed away 55 as rapidly as formed; being flooded through the socket of the chuck and washed down the incline chute 71 where they are received in a settling tank and the liquid coolant is drained through suitable strainers and 60 returned to the action of the pump 69 so that it is used continuously. This action reduces the liability of stoppage to a minimum, and in combination with the automatic means for terminating the feed of the blanks in 65 case of any abnormal action a very reliable

organization results. The means for overcoming the tendency of the train of nut-blanks to congest on the shank of the tap will now be detailed.

The automatic device for promoting the discharge of the blanks.—This device insures a travel of the train of threaded blanks on the off-set portion of the tap to prevent congestion of the blanks at the point of leaving the threads of the tap. As has been explained, considerable friction is created where the blanks pass through the guide C and during each cycle of operation, this friction decreases in intensity from one maximum to an inappreciable or negative amount, and then increases in intensity to another maximum. The one maximum is determined by the pressure of the plunger when starting a nut-blank onto the tap, and the other maximum is determined by the force required to pull the nut-blanks through the socket of the nut-holder during the thread-cutting period. The automatic stop device proposed in this connection exerts a force on the nut-blanks tending to urge them in a discharging direction during the period that the friction is being varied from the one maximum to the other. This friction will undergo quite irregular fluctuations during the normal action of the machine, and at times this device will be effective to urge the blanks in a discharging direction against the friction somewhat sooner in the cycle of operations than at other times. Thus, it 90 may be inadequate to discharge the blanks always at the same instant in the cycle, but in any event, it will come into play as soon as the friction is sufficiently relieved by the action of the plunger. The specific construction preferred by this invention may 95 now be detailed.

A carriage 72 is arranged to reciprocate at one side of the L-shaped tap, as by means of the guides 73 provided by an off-set portion of the frame of the machine. This reciprocating carriage has a finger F pivoted to it at 74 about an axis extending transversely to the shank of the tap and this finger projects toward the tap and terminates 100 at a point adjacent the elbow thereof so that, when it swings inwardly, it may engage one of the blanks of the train and be made effective to push the same in a discharging direction under an appropriate impetus of the carriage 72. This finger is in the nature of a pawl and is resiliently maintained in contact with the blanks by means of a suitable spring 75. The forward stroke of this finger and the carriage 72 is preferably in the 105 nature of an impositive action and is produced as by means of a lever 76 having a toe 77 bearing against the carriage; which lever is urged anti-clockwise by means of a spring or weight 78. A handle 79 extending from 110

the lever 76 conveniently enables the pressure of the weight to be relieved for purposes of inspection or adjustment. The return stroke of the finger is produced positively by means of a lever 80 pivoted at 81 to the frame of the machine and terminating in a shoe or roller 82 located in the path of a cam 83 mounted on the power-shaft 40 so that at each revolution of the latter the lever 80 will be withdrawn out of contact with the pin 84 to permit the carriage to advance under the control of the weight and thereby create the desired impositive propulsion of the train of blanks on the tap. 10 The instant the friction is sufficiently reduced, the weight 78 will be enabled to advance the blanks, and then the cam 83 will again withdraw the finger F to its original position. The finished nut-blanks 20 will successively drop off of the end of the off-set portion 4 of the tap and will be received by the chute 85.

The means preventing side cramping of the tap.—This comprises an anti-friction support for the blanks on the shank of the tap adjacent the elbow thereof and this support is here instanced as a roller G having a groove 86 of sufficient size to receive and guide a train of blanks in alinement 30 with the axis of the tap proper. This roller is suitably journaled on the frame of the machine as by means of an extension 87 bolted thereto. In conjunction with the support G a secondary support, shown in 35 perspective by Fig. 10 and indicated by H, may be arranged adjacent the delivery end of the socket of the chuck so as to support the tag through the train of blanks by means of a semi-circular shelf 88. 40 The guide member C, which provides the bearing surfaces 6, 8 and 9, preferably has a tubular form and is removably supported by a bracket 89 secured to the frame of the machine. A pin 90 will suffice to hold the 45 guide C in position during the operation of the machine, and a slot 91 will enable the guide to be removed for purposes of replacement or repair by bringing the pin 90 in alinement with said slot.

50 Referring again to Fig. 11, it is to be noted that the aperture 7 of the nut-chuck has a peculiar conformation in that it provides two parallel flats 91 and 92 which are spaced apart only sufficiently to give a little 55 clearance for the adjacent faces of the nut-blanks. Then flats extend for the full length of the bore of the nut-chuck and have been formed to reduce the friction to such a degree as to render unnecessary the feeding 60 finger in certain cases. To direct the nut-blank along a central line, whereby it may properly engage the tap, side walls 93 and 94 may be extended for a short distance in close proximity with the blanks and, to provide ample space for the discharge of the 65

chips, may thereafter flare away funnel-like toward the discharge side of the nut-chuck as indicated by the dotted lines 95 and 96.

Having thus revealed this invention, I claim as new and desire to secure the following combinations of elements, or equivalents thereof, by Letters Patent of the United States:—

1. A nut-tapping machine of the nature disclosed combining a tap; a nut-blank holder; means for rotating one of said parts relatively to the other; a guide for conveying a train of threaded blanks adapted to position said tap through the agency of said blanks; means for intermittently feeding 75 blanks to said holder; and automatic means for engaging the nut blanks after being threaded by said tap to urge them through said guide. 80

2. A nut-tapping machine of the nature disclosed combining a tap; a nut-blank holder; means for rotating one of said parts relatively to the other; a nut-blank chute for feeding a train of nuts to the entrance of 90 said holder; an impositively actuated member adapted impositively to urge the end nut-blank into said holder and into engagement with said tap; and means restraining the progression of the blanks in said chute whenever said member is prevented from 95 making a full forward stroke.

3. A nut-tapping machine of the nature disclosed combining a tap terminating in an offset portion bent at an angle to its threaded portion; a nut-blank holder; means 100 for rotating one of said parts relatively to the other; and an anti-friction roller-bearing adapted to contact adjacent said holder with the train of nut-blanks guided by said tap anti-frictionally to coöperate with said 105 blanks to maintain the position of said tap, said roller-bearing having its axis extending parallel with the said offset portion of said tap.

4. A nut-tapping machine of the nature disclosed combining a tap; a nut-blank holder provided with an aperture having two oppositely located parallel bearing surfaces 91 and 92 adapted to contact the opposite faces of a polygonal nut-blank to prevent it from rotating relatively to the holder without restraining an axial translation thereof, the connecting walls of said aperture being relieved to provide clearance 115 for the nut-blank; means for rotating one of said parts relatively to the other; and means for feeding nut-blanks into engagement with the aperture in said holder. 120

5. A nut-tapping machine of the nature disclosed combining a tap having an offset 125 shank portion; two guides arranged in an angular relation to one another, one of said guides being located adjacent the offset portion of said tap and adapted through a train of nut-blanks to maintain the position of 130

- said tap; means for rotating one of said guides with relation to the other; and means for intermittently urging said blanks along the offset portion past said adjacent guide.
- 5 6. A nut-tapping machine of the nature disclosed combining a tap having an offset shank portion; a nut-blank holder; means for intermittently feeding nut-blanks to said holder; a member coöperating with the nut-blanks located on the offset portion of said tap and adapted to coöperate in positioning the taps; and means assisting to overcome the friction between the nut-blanks and said member to promote the feeding of 10 said blanks. 70
- 10 7. A nut-tapping machine of the nature disclosed combining a tap; a nut-blank holder having a socket in co-axial relation with the tooling end of said tap; means for producing relative rotation between said tap and said holder; means for feeding blanks into said socket to engage with the tooling end of said tap; and an intermittently operating finger adapted to impact 15 a train of nut-blanks on the shank of said tap to coöperate in moving the same. 80
- 15 8. A nut-tapping machine of the nature disclosed combining a tap; a nut chuck; intermittently acting means for intermittently feeding nut-blanks to said chuck whereby they may be threaded by a relative rotation 20 between said chuck and said tap; a chute for feeding nut-blanks to said means; a normally-stationary part adapted to obstruct the feeding of said blanks in said chute and mechanism adapted to move said part into obstructing position when said means fails to execute its normal cycle of movement. 85
- 20 9. A nut-tapping machine of the nature disclosed combining a nut-blank holder provided with a socket having opposite surfaces adapted to guide a blank and having a relieved face; a tap having its tooling end projecting co-axially into said socket; means for rotating said parts relatively to one another; a tubular plunger adapted to project a nut-blank into the socket of said holder and into engagement 25 with the tap therein; and means for forcing a copious flow of coolant through the bore of said plunger and into said socket to cool the tap and wash away the chips through the clearance space provided by the relieved face of said socket. 90
- 25 10. A nut-tapping machine of the nature disclosed combining an L-shaped tap; a plunger for urging an apertured nut-blank into engagement with the threaded end of 30 said tap; a member adapted through the agency of nut-blanks on the off-set portion of said tap to resist displacement of said tap under the thrusts of said plunger; means effective to produce a relative rotation between said tap and the nut-blanks on the 105
- 30 threaded portion thereof, said means tending to displace said tap in the direction of retreat of said plunger until resisted by said member; and an impositive device adapted to urge the train of nut-blanks along the off-set portion of said tap at the instant said plunger starts to retreat. 75
- 35 11. A nut-tapping machine of the nature disclosed combining a tap having an off-set shank portion; a nut-blank holder having a socket for containing a nut-blank and for supporting the threaded end of said tap through the agency of said nut-blank; a member positioned adjacent the off-set portion of the shank of said tap providing a bearing surface adapted to contact with a nut-blank on said portion to position the other end of said tap; means for producing a relative rotary movement between said member and said holder about the axis of the latter; and an anti-friction device located between said member and said holder and bearing against a nut-blank on the shank of said tap adjacent the elbow thereof. 85
- 40 12. A nut-tapping machine of the nature disclosed combining a tap having a threaded end and an off-set shank portion; a plunger adapted to urge a blank against the end of said tap to engage the threads thereof; means for causing said blank to rotate relatively to said tap to travel along the threads thereof; means presenting a first and second bearing surface adapted to co-act with a blank on the off-set portion of said shank to relieve the advance shift of said tap under the action of said plunger as well as the retreat shift of said tap under the pull of the blank being threaded thereby; and means effective to feed blanks along the off-set shank portion during the instant said 100
- 45 tap is shifted under the impetus of said plunger. 105
- 50 13. A nut-tapping machine of the nature disclosed combining a tap having its shank providing an elbow; means for positioning said tap through the agency of blanks trained thereon; means for intermittently supplying said tap with blanks; means for effecting a relative rotation between the blanks and the threaded portion of said tap; and means intermittently engaging threaded blanks to feed the same along the shank away from the threaded portion of the tap. 110
- 55 14. A nut-tapping machine of the nature disclosed combining a chuck having a socket whereby nut-blanks may be passed through said chuck and restrained from rotating relatively to said chuck; a tap arranged co-axially with said socket adapted intermittently to thread said blanks; a chute for feeding blanks into co-axial registry with said socket; an impositively actuated plunger adapted to urge a registry blank into said socket and into engagement with said tap; a finger normally aside from the path 115

- of the blanks in said chute; and means for automatically interposing said finger in said path whenever said plunger fails to execute its full forward stroke.
15. A nut-tapping machine of the nature disclosed combining a tap having an off-set shank portion; a support operating through blanks entrained on said tap for positioning the off-set portion thereof; a holder for blanks located at the threaded portion on said tap; means for producing a relative rotation between said supports; a finger adapted intermittently to engage one of the blanks entrained on said tap between said supports and adapted impositively to urge said blank away from the threaded portion of said tap; and means for intermittently engaging a blank with the threaded portion of said tap.
20. 16. A nut-tapping machine of the nature disclosed combining a rotatable member having a nut-receiving socket; a non-rotatable tap having its threaded portion extending into the exit end of said socket; a chute enabling nut-blanks to be placed at the entrance of said socket; means for intermittently displacing nut-blanks into said socket whereby they may be rotated by said member and caused to be fed upon and threaded by said tap; a part normally out of the path of the blanks in said chute; a power-driven element, and interponent mechanism adapted when actuated by power derived from said element to shift said part into the path of said blanks, said means controlling the operative connection between said mechanism and said element.
25. 17. A nut-tapping machine of the nature disclosed combining a member providing an elongated polygonal socket; a plurality of elements having rounded portions and mounted on said member at the entrance of said socket and adapted to receive and bring a polygonal nut-blank into angular registry with the guides of said socket; means for feeding nut-blanks past said elements and into said socket whereby they may be prevented from rotating relatively to said mem-
- ber; a tap adapted to be engaged by said blanks; and means for producing a relative rotation between said member and said tap to thread said blanks.
18. A nut-tapping machine of the nature disclosed combining a rotatable member having a socket having guides adapted to engage the sides of a polygonal nut-blank and cause it positively to rotate with the member; a plurality of elements mounted at the entrance to said socket for acting on said blank to bring it into angular registry with the guides of said socket; means for feeding nut-blanks to said member, and means for tapping said blanks while being rotated by said member.
19. A nut-tapping machine of the nature disclosed combining a rotatable member having an elongated socket adapted to receive and positively rotate a polygonal nut-blank; a plurality of hardened balls mounted symmetrically on said member concentric with its axis and adapted to receive and bring a succession of nut-blanks into registry with said socket; and means for tapping said blanks while being rotated by said member.
20. A nut-tapping machine of the nature disclosed combining a rotary chuck having an elongated socket adapted to receive and positively rotate hexagonal nut-blanks; six rounded elements symmetrically disposed at the entrance to said socket; a tap extending into said socket in concentric relation therewith; and a reciprocating member terminating in a cylindrical end adapted to impact and urge a blank into said socket and into engagement with said tap whereby it may be rotated by said chuck and caused to be drawn through said socket by the screw-like action of said tap.
- In witness whereof, I hereunto subscribe my name, as attested by the two subscribing witnesses.
